(57) **CLAIM**

I claim the ornamental design for a combined razor cartridge guard and docking, as shown and described.

DESCRIPTION

FIG. 1 is a front perspective of a combined razor cartridge guard and docking, according to an embodiment of my new design;

FIG. 2 is a bottom perspective of a combined razor cartridge guard and docking, according to an embodiment of my new design;

FIG. 3 is a front elevational view of a combined razor cartridge guard and docking, according to an embodiment of my new design;

FIG. 4 is a rear elevational view of a combined razor cartridge guard and docking, according to an embodiment of my new design;

FIG. 5 is a top plan view of a combined razor cartridge guard and docking, according to an embodiment of my new design;

FIG. 6 is a bottom plan view of a combined razor cartridge guard and docking, according to an embodiment of my new design;

FIG. 7 is a left elevational view of a combined razor cartridge guard and docking, according to an embodiment of my new design; and,

FIG. 8 is a right elevational view of a combined razor cartridge guard and docking, according to an embodiment of my new design.

The broken lines illustrate the environment of the combined razor cartridge guard and docking and form no part of the claimed design.
